[57] CLAIM

The ornamental design for a front end loader, as shown and described.

DESCRIPTION

FIG. 1 is a perspective view of a front end loader showing my new design;

FIG. 2 is an enlarged side elevational view taken from the left of FIG. 1;

FIG. 3 is an enlarged rear elevational view thereof;

FIG. 4 is an enlarged bottom plan view thereof;

FIG. 5 is an enlarged top plan view thereof;

FIG. 6 is an enlarged front elevational view thereof.

*Fig. 1.**Fig. 2.**Fig. 3.**Fig. 4.**Fig. 5.**Fig. 6.*
